Primary Examiner — Michael C Stout*Assistant Examiner* — Katrina N Gonzalez(74) *Attorney, Agent, or Firm* — Lathrop GPM, LLP(57) **CLAIM**

The ornamental design for a liquid supplement tank, as shown and described.

DESCRIPTION

FIG. 1 is a perspective view of a liquid supplement tank showing the new design.

FIG. 2 is a front view of the liquid supplement tank of FIG. 1, the rear view being a mirror image of this front view.

FIG. 3 is a side view of the liquid supplement tank of FIG. 1, the opposite side view being a mirror image of this side view.

FIG. 4 is an end view of the liquid supplement tank of FIG. 1.

FIG. 5 is an opposite end view of the liquid supplement tank of FIG. 1; and,

FIG. 6 is another perspective view of the liquid supplement tank of FIG. 1.

The broken lines illustrate an environmental structure that forms no part of the claimed design.

1 Claim, 6 Drawing Sheets(56)
